PINHOLE GRINDER MANDREL

Joseph Sunnen, Kirkwood, Mo.

Application February 6, 1933, Serial No. 655,392

9 Claims. (Cl. 51—184.3)

My invention has relation to improvements in machines for grinding small holes, such as the wrist pin holes of engine pistons, and it consists in the novel features of construction more fully set forth in the specification and pointed out in the claims.

The present invention is directed specifically to the holder or mandrel for the abrasive element and is an improvement over the mandrel described and claimed in my co-pending application, Serial No. 578,923, filed December 4, 1931.

Grinding operations are performed by means of my improved grinder in the same manner as they are performed by the grinder of the application just referred to. That is to say, the mandrel is rigidly connected to a rotatable shaft and the piston pin holes are ground by moving the piston back and forth over the mandrel so that the abrasive element will traverse said holes as it is revolved. It is quite apparent that as the operator moves the piston back and forth to effect the grinding of the holes he will exert some pressure on the mandrel (as the piston is allowed to float) and of course impose strains therein so that means must be embodied in the mandrel and also in the elongated abrasive element to prevent permanent distortion of the mandrel or breaking of the stone. It is one of the objects of the present invention to provide such means. In the present invention, as in that heretofore referred to, the abrasive element is adjustable radially with respect to the mandrel in order that it may be adapted for grinding holes of different sizes, and it is one of the objects of the present invention to provide a means of effecting such adjustment that will give a greater range of adjustment than that heretofore obtained.

It is also an object of the invention to embody in the mandrel means for securing the abrasive element therein in a manner that said element may be easily and quickly removed when desired. A further object is to provide an abrasive element that although rigidly held in the mandrel possesses flexibility so that it is capable of accommodating itself to the slight flexing action that may take place in the mandrel during operation. These and other advantages will be better apparent from a detailed description of the invention in connection with the accompanying drawings, in which:

Figure 1 is a side elevation of my improved pin hole grinder mandrel connected to a suitable actuating device therefor; Fig. 2 is a vertical longitudinal section through the mandrel and actuating device showing the connections between

the mandrel and said device; Fig. 3 is a plan view of the mandrel together with the connecting link of the mechanism for effecting radial adjustment of the abrasive element; Fig. 4 is a vertical longitudinal section through a part of the mandrel taken on the zig-zag line 4—4 of Fig. 3; Fig. 5 is a bottom plan of the mandrel; Figs. 6, 7 and 8 are vertical cross-sectional views taken on the lines 6—6, 7—7 and 8—8 respectively of Fig. 3; Fig. 9 is a perspective view of the inner end of the abrasive element showing the hook whereby said element engages the body of the mandrel; Fig. 10 is a vertical longitudinal section through the mandrel taken on the line 10—10 of Fig. 3; Fig. 11 is an enlarged middle longitudinal section of the inner enlarged end of the mandrel together with the connections to the driving mechanism; and Fig. 12 is a horizontal cross-section taken through the inner end of the mandrel and coupling nut on the plane indicated by the line 12—12 of Fig. 11.

Referring to the drawings, 1 represents my improved mandrel terminating at its inner end in spaced flanges 2, 2', both of which are received within a socket 3 of a coupling nut 4 having threads 4' formed in the inner end thereof whereby the coupling nut is secured on the threaded extremity 5' of a driving spindle 5 mounted in a bearing 6 which forms a part of the actuating device for the mandrel. An annular flange 7 is formed within the nut 4 against which the end of spindle 5 abuts when the nut 4 is tightly screwed thereon. A disk 8 is secured within the nut 4 in abutting relation with the flange 7 (preferably by being driven into said nut) and said disk has a slot *a* formed inwardly from its periphery to approximately the center thereof through which is driven a key 8'. One end of the key 8' projects into the socket 3, and the other end of said key fits tightly in a recess *r* formed in the flange 7 (Figs. 11 and 12). It will be observed by referring to Fig. 11 that when the mandrel is secured within the nut 4 the outer end of key 8' enters the part 10' of a longitudinally disposed slot 10 extending throughout the full length of the mandrel except at its outer extremity where the slot is closed by wall 11, and since the inner end of the key fits in the recess *r* of flange 7 the mandrel is securely connected to said nut 4, the key 8' serving as a driving lug therefor. In order to prevent the mandrel from moving longitudinally out of the socket 3 of nut 4 a set-screw 9 is passed through the nut and caused to firmly engage with the mandrel between the flanges 2 and 2'. There are three spaced shallow bosses 12, 12, 12

formed on the bottom of the slot 10 and a rib 13 is formed on one side wall of the slot adjacent to the innermost boss 12 for a purpose presently to appear. The slot 10 is adapted to receive an abrasive element E comprising two stick members 14, 14 having their adjacent ends loosely coupled by means of a tongue 15 projecting from the end of one member and a recess 16 formed in the end of the other member together with a hinge pin 17 passed through said tongue and the end of the member 14 adjacent thereto, as shown in Fig. 2. Abrasive stones 18, 18 of carborundum, or equivalent material, are securely fixed to the upper surfaces of the sticks 14, 14 by cement or otherwise so as in effect constitute an integral part of the sticks. The free end of inner stick 14 is provided with an upwardly tapered recess 19 in one side for the purpose of receiving the rib 13 projecting from the side of slot 10 whereby the abrasive element E is securely held in the mandrel at its inner end. The free end of the outer stick 14 is notched at 20 so as to provide a hook for engaging the downwardly bent extremity 21' of link 21 which serves as an anchor for the abrasive element E. The outer end 22 of the anchor link 21 is perforated so that it may be slidably mounted on a pin 23 secured into the end wall 11 of the mandrel 1 and projecting into the slot 10. A coiled spring 24 is mounted on the pin 23 between the inner head 25 thereof and the downwardly bent end 22 of the link 21 so as to continually urge said link 21 outwardly and thereby exert an outward pull on the abrasive element E, thus holding said abrasive element firmly in the mandrel. The link 20 is provided with an elongated opening 26 whereby it may be engaged by a suitable tool for disengaging the link from the abrasive element when it is necessary to remove said element from the mandrel.

It will be observed (Figs. 2, 3 and 4) that each stick 14 has wedge-shaped bosses 27, 27' formed on the side opposite to that containing the notch 19 and the bosses being adjacent to the ends of each stick. The bottom edges e, e' of the bosses 45 are inclined downwardly toward the outer end of the mandrel (when the abrasive stick is inserted therein), and the edges e', e of the adjacent bosses 27', 27 together form a continuous inclined surface. The presence of the bosses 27, 27' obviously results in the formation of a clear space between the sides of the sticks 14, 14 and the adjacent side of the recess 10. A wedge-bar 28 is positioned in this space S with its bottom plane edge 29 adapted to ride on the bosses 12 and its wedge-formations 30, 31, 32 beneath the wedge-bosses 27 and 27' of each stick 14 (Fig. 10). It is quite apparent that moving the wedge-bar 28 outwardly (that is, toward the free end of the mandrel) would cause the wedges 30 to slide under the wedge-bosses 27 and 27' to raise them and, of course, the sticks 14, 14 so that the abrasive element is adjusted radially outwardly from the mandrel. There is, of course, sufficient flexibility in the connection between the hook 21 and adjacent stick 14 to permit this stick to move freely under the influence of the wedge-bar 28. The inner end of wedge-bar 28 is provided with a hook 33 to engage a notch 34 formed on the free end of a link 35 which forms the connection between the wedge-bar 28 and adjusting screw 36 operating through a threaded opening 37 in a socket 38 on the inner end of the link 35. As in my pending application, Serial No. 578,923, the link 35 is caused to move back and forth by turning a knurled knob 39 secured to a stub shaft 40, the

inner end of which is flexibly connected at 41 to the screw 36.

The mandrel 1 has longitudinally extending ribs 42 and 43 formed on its periphery in spaced relation, the length of said ribs being co-extensive with that of the abrasive element E, and the rib 42 being circumferentially closer to the stone 18 than the rib 43. It will be observed that the ribs 42, 43 are slightly narrower for a short distance inwardly from their outer extremities, as shown at 42', 43'. The purpose of the ribs is to serve as guide elements for the abrasive element E as the mandrel is rotated in a piston pin hole for the purpose of grinding the same to a true cylindrical shape. In the grinding operation the device contacts with the wall of the hole along the three lines defined by the stone 18 and the ribs 42, 43 irrespective of the position to which the abrasive element is adjusted as the three point contact makes the mandrel self-centering with respect to the piston floating thereon. In the grinding operations there is a tendency for the outer end of the stone to break down and wear more rapidly than the balance of the stone because it is at this end that the piston is applied to and removed from the mandrel. It is for this reason that the outer ends 42', 43' of the guides are reduced somewhat in width so that the wear between the end of the stone and the guides will be somewhat equalized.

In the operation of the grinding device the operator positions the piston on the mandrel so that the mandrel traverses both the piston pin holes, and while the mandrel rotates the operator manually moves the piston back and forth over practically the entire extent of the abrasive element E. During this operation it is apparent that some pressure will be caused to bear on the mandrel and cause it to bend slightly because of its small diameter in comparison with its longitudinal extent. If the abrasive element E were made in one piece the pressure exerted on the mandrel would cause it to fracture since the abrasive stones possess little or no flexibility in themselves. It is to prevent fracturing of the abrasive stones that I form the abrasive element E of two members which are flexibly connected, as above described. The mandrel 1 being made of a suitable metal possesses inherent flexibility and the wedge-bar 28, being greatly reduced in width between the wedge-formations 31 and 32, is also sufficiently flexible to bend with the mandrel should sufficient pressure be applied thereto by the operator during his work. Should the operator desire to remove the abrasive element E at any time he simply disengages the link 21 from the hook 20 whereupon the abrasive element may be lifted out of the recess 10.

The coupling mechanism, essentially the nut 4 and link 35, make it possible for the mandrel to be connected to the driving mechanism easily and quickly. For instance, the operator merely inserts the flanges 2, 2' in the socket 3 of nut 4 (first sliding the wedge-bar 28 until the hook 33 extends beyond the flange 2' and making sure that the link 35 is adjusted outwardly far enough for its notch 34 to register with said hook 33), after which the mandrel is rotated (as shown by the arrows in Fig. 12) so that said notch 34 and hook 33 will come into engagement (as shown in Fig. 3). The operator now pushes the mandrel inwardly until the flange 2' abuts against the disk 8, at which time the key 8' will have entered slot 10' to couple the mandrel to the nut 4 and, of course, to the driving spindle 5. The slot 10' is sufficiently wide to also receive within it the

link 35, as shown, as this link and also adjusting screw 36 rotate in unison with the mandrel during the grinding operations.

Having described my invention, I claim:

5. 1. In a grinding machine, a mandrel having a longitudinally disposed recess, an abrasive element in said recess, and means for holding the abrasive element in place, said abrasive element comprising a plurality of connected members.
10. 2. In a grinding machine, a mandrel having a longitudinally disposed recess, a jointed abrasive element in said recess, and means for holding the abrasive element in place.
15. 3. In a grinding machine, a mandrel having a longitudinally disposed recess, a pair of longitudinally extending guide elements on the periphery of the mandrel circumferentially spaced from each other and from said recess, and a plurality of abrasive members disposed end to end in said recess and collectively co-extensive with the guide elements.
20. 4. In a grinding machine, a mandrel having a longitudinally disposed recess, a pair of longitudinally extending guide elements fixed on the periphery of the mandrel circumferentially spaced from each other and from said recess, a plurality of abrasive members disposed end to end in said recess and collectively coextensive with the guide elements, and means for simultaneously adjusting said abrasive members radially of the mandrel.
25. 5. In a grinding machine, a mandrel having a longitudinally disposed recess, a flexible abrasive element in said recess, said element having a plurality of wedge-bosses in spaced relation, a wedge-bar disposed in said recess having a plurality of wedge-surfaces to engage with the wedge-bosses for moving the abrasive element radially of the mandrel with a longitudinal movement of the wedge-bar, and means for holding the abrasive element in place, said means exerting tension on the abrasive element in the same direction that the wedge-bar is movable to effect outward adjustment thereof.
30. 6. In a grinding machine, a mandrel having a longitudinally disposed recess, a flexible abrasive element in said recess, said element having a plurality of wedge-bosses in spaced relation, a wedge-bar disposed in said recess between the abrasive element and side of said recess, said wedge-bar having a plurality of wedge-surfaces to engage with the wedge-bosses for moving the abrasive element radially of the mandrel with a longitudinal movement of the wedge-bar, and means for holding the abrasive element in place.
35. 7. In a grinding machine, a mandrel, driving mechanism therefor, said mandrel having a longitudinally disposed slot, a grinding element mounted in said slot, a member slidably longitudinally to effect changes in the position of the grinding member, means for coupling the mandrel to said driving mechanism, means associated with the driving mechanism for actuating said slidable member, and interlocking devices on the slidable member and actuating means for said member, said interlocking devices being arranged to interlock with a relative rotation thereof.
40. 8. In a grinding machine, a mandrel, driving mechanism therefor, a grinding element mounted in said mandrel, said driving mechanism including a driving spindle terminating in a socket at one end, a driving lug in said socket, said mandrel having a slotted flange at one end adapted to enter said socket, said lug entering the slot in the mandrel flange to couple the mandrel to the driving spindle, and means associated with the driving means for effecting changes in the position of the grinding element, said last named means being disposed in the slotted flange.
45. 9. In a grinding machine, a mandrel having a longitudinally disposed recess, a driving mechanism for said mandrel, a grinding element and a longitudinally slidable member mounted in said slot, means for coupling the mandrel to said driving mechanism, and means associated with the coupling means for actuating the slidable member, said coupling means including a drive lug, said actuating means including a connecting link for engagement with the slidable member, means for maintaining the connecting link in radial alignment with the drive lug whereby both link and lug may enter the mandrel recess on moving same longitudinally toward the coupling member.

JOSEPH SUNNEN.
